United States Patent Office.

THEODORE R. TIMBY, OF SARATOGA, NEW YORK.

Letters Patent No. 91,580, dated June 22, 1869.

IMPROVEMENT IN TURBINE WATER-WHEELS.

The Schedule referred to in these Letters Patent and making part of the same.

To all whom it may concern:

Be it known that I, THEODORE R. TIMBY, of the town and county of Saratoga, in the State of New York, have invented a new and useful Improvement in Turbine Water-Wheels; and I declare that the following is a sufficiently full and exact description thereof, to enable one skilled in the art to which my invention appertains to carry it into effect, reference being had to the accompanying drawings, which are made a part of this specification.

The subject of my invention is a duplex central-discharge wheel, the impact faces of whose buckets are of angular form, and are provided with concentric flanges, which prevent centrifugal or tangential slip or pressure of the water, and, in connection with the surrounding eccentric flume or casing, a converging or wedge-shaped space, the effect of which is to hold the water to its place, so that it will exert a constant and unbroken pressure upon the buckets.

In the drawings—

Figure 1 represents a horizontal section of my improved wheel in the plane indicated by the line x x , fig. 2.

Figure 2 represents a vertical section at y y , fig. 1.

A is the stationary casing, in which is the converging scroll or flume B, through which the water enters, and is delivered to the buckets.

The shaft C is supported below by a step, D, and above has its bearing in a yoke or frame, E, in customary manner.

The wheel proper consists of a central horizontal plate, F, firmly secured to the shaft C, and buckets G H I, mounted upon the periphery of the said plate, which is formed to fit them, as represented in fig. 1, and connecting rims M N.

The impact faces G of the buckets form planes radial, or nearly so, to the wheel, so as to present surfaces at right angles to the line on which the water strikes them, and are flanked by lips or flanges H, arranged concentrically to the wheel, and serving to prevent any tangential slip of the water from the faces G, or any radial pressure upon the column within the flume.

The concentricity of these flanges, and of the outer surfaces J of the forward ends of the buckets, causes them to offer no obstruction to the rotation of the wheel, and also adapts them to form, in connection with the eccentric flume or casing, a converging or wedge-shaped space, the effect of which is to hold the water to its place, so that it will exert a constant and unbroken pressure upon the buckets.

The inner walls I of the buckets are made of parabolic or other curved form, to permit the free inward flow of the water after its force has been exerted upon the impact faces of the buckets.

The water is then discharged freely above and below, through the central apertures K L.

The red arrow in fig. 1 indicates the direction of rotation of the wheel.

The blue arrows show the course of the water, and the dotted lines parallel with the inner face of the flume indicate the portion of the water that acts upon each bucket.

The buckets are connected at their upper and lower edges by the rims M and N of the wheel.

Having thus described my invention,

What I claim as new therein, and desire to secure by Letters Patent, is—

1. The buckets, constructed with radial, or nearly radial, impact faces G, concentric or tangential lips H to prevent slip, and curved inner walls I, to permit the free passage of the spent water inward to its discharge, substantially as set forth.

2. The segmental cheeks H J, in combination with the eccentric flume or casing, as explained.

3. The central plate, in connection with the buckets G H I and discharge-apertures K L, arranged as shown.

THEODORE R. TIMBY.
